UNITED STATES PATENT OFFICE

ALBERT J. ERRETT AND CYRIL P. PESEK, OF MINNEAPOLIS, MINNESOTA, ASSIGNORS TO HEN HOUSES, INC., OF MINNEAPOLIS, MINNESOTA, A CORPORATION OF SOUTH DAKOTA

DESIGN FOR A RESTAURANT BUILDING

Application filed September 5, 1930. Serial No. 36,881. Term of patent 14 years.

To all whom it may concern:

Be it known that we, ALBERT J. ERRETT and CYRIL P. PESEK, citizens of the United States, residing at Minneapolis, in the county of Hennepin and State of Minnesota, have invented a new, original, and ornamental Design for Restaurant Building, of which the following is a specification, reference being had to the accompanying drawing, forming part thereof, wherein—

Fig. 1 is a perspective view of a restaurant building showing our new design;

Fig. 2 is a front elevation of the same, and
Fig. 3 is a side elevation of the same.

What we claim is:—

The ornamental design for a restaurant building substantially as shown.

ALBERT J. ERRETT.
CYRIL P. PESEK.
